DESIGN FOR A COMBINATION KITCHEN TOOL

Ernest Cullen, San Diego, Calif., assignor to John B. Smiley, Los Angeles, Calif.

Application May 20, 1938, Serial No. 77,309

Term of patent 7 years

To all whom it may concern:

Be it known that I, Ernest Cullen, a citizen of the United States, residing at San Diego, in the County of San Diego, State of California, have invented a new, original, and ornamental Design or a Combination Kitchen Tool, of which the following is a specification, reference being had to the accompanying drawing, forming part thereof, in which:

Fig. 1 is a perspective view, taken from one side and one end, of a combination kitchen tool, showing my new design;

Fig. 2 is a perspective view thereof, taken from the opposite side, and the opposite end;

Fig. 3 is a side view thereof, taken from the side shown in Fig. 1; and,

Fig. 4 is an edge view thereof.

I claim:

The ornamental design for a combination kitchen tool, substantially as shown.

ERNEST CULLEN.
